UNITED STATES PATENT OFFICE.

GEORGE A. LITCHFIELD, OF SOUTHBRIIDGE, MASSACHUSETTS, ASSIGNOR TO LITCHFIELD SHUTTLE COMPANY, OF SOUTHBRIIDGE, MASSACHUSETTS, A CORPORATION OF MASSACHUSETTS.

LOOM SHUTTLE.

Application filed October 11, 1924. Serial No. 743,059.

To all whom it may concern:

Be it known that I, GEORGE A. LITCHFIELD, a citizen of the United States, and resident of Southbridge, in the county of Worcester and State of Massachusetts, have invented certain new and useful Improvements in Loom Shuttles, of which the following is a specification.

This invention relates to loom shuttles of the type carrying a pivotal spindle for operatively supporting either a cop tube or a bobbin which carries the package of filling yarn in the shuttle.

As the spindle is intended to carry either a cop tube or a bobbin, provision is made for retaining either one of these yarn-carrying devices against longitudinal displacement in the shuttle which the repeated shocks of suddenly starting and stopping the shuttle tends to produce. As bobbins are invariably larger in diameter at their base portion than are the cop tubes commonly employed, it has been proposed to use spring hooks or fingers secured to the heel end of the spindle head, the shorter and innermost of which extends inwardly to grip the end portion of the cop tube, while the outer and longer arm extends inwardly far enough to engage a circumferential groove in the base of the bobbin. It has also been proposed to use a single spring arm, bent so as to form two inwardly projecting retaining members, properly located to grip respectively a cop tube or a bobbin.

The present invention is intended to obviate certain difficulties that are involved in the use of either of the above constructions for retaining cop tubes and bobbins against displacement on the spindle blade, the present arrangement being such as to make possible a stronger tension for resisting any releasing movement on the part of either the cop-retaining member or the bobbin-retaining member, while at the same time increasing the durability and lessening the likelihood of breakage of these parts which, in previous constructions, are under constant flexing strains to permit removal of the yarn-carrier whether a cop or bobbin.

To this end the invention comprises, generally speaking, a pivotal blade mounted on a transverse pin forming a pivotal axis located in the rear part of the shuttle, combined with a cop-gripping member pivotally mounted on said pivotal axis, and a bobbin-

engaging spring arm secured to the heel end of the spindle so that as the spindle is swung out of the shuttle to open position the relation of the spring arm to the pivotal cop-gripping member is changed from a parallel to an angular relation.

Another feature of this invention is that the pivoted cop-gripping member need not be made of spring material but can be made rigid to give it any desired degree of strength, while when the spindle is opened the pivotal member is so held as to engage, at its forward end, the forward end portion of the spring arm, cause the same to yield and permit the spindle to continue its swinging movement to open position with the least possible strain on the spring arm by reason of the relatively long leverage from its rear end to the point of contact with its special member, namely, the pivotal cop-gripping member.

These and other features of the invention will be explained in the following specification and will be defined in the claims hereto annexed.

In the accompanying drawings I have illustrated a simple construction and arrangement embodying the principles of this invention, in which:

Figure 1 is a vertical central section through the rear end portion of a shuttle having a blade for the reception of either cop or bobbin with the parts in normal position for weaving.

Figure 2 is a central vertical section showing the same parts with the spindle in open position, that is, swung out of the shuttle body to permit removal of the yarn-carrier and application of a full cop-tube or bobbin.

Figure 3 is a detail view showing, in plan, the spindle and its cooperating retaining members with the outline of a bobbin shown in dotted lines.

In the practice of this invention, as illustrated in the drawings, the shuttle body, which is of usual or suitable construction, has its rear end portion recessed properly to support the head 3, of the spindle from which projects forwardly the yarn-carrying blade 4 on which is shown a tight fitting 105 cop tube 5.

The heel end 3^a of the spindle head abuts against a shelf or ledge 1^a formed by cutting out the solid end portion of the shuttle, which ledge acts as a stop to limit the swing- 110

ing movement of the spindle beyond the medial or central line of the shuttle under the pressure of the coil spring 7 and the inserted plunger 6, which engages a usual transverse socket formed in the head 3 of the spindle. This is an old and well known construction forming no part of the present invention, and any other suitable construction for normally positioning the spindle in central alignment may be equally well employed.

The transverse pin 2, mounted in this rear end of the shuttle body, forms a pivotal axis about which the spindle can be swung between the limits of its movement.

The bobbin-gripping and retaining member 9 is formed with parallel upturned spaced ears 9^a mounted on the pivotal axis 2 astride of the block or head portion 3, of the spindle, but is loose both with relation to the spindle and to the axis 2, so as to allow it to have a certain independence of movement with relation both to the pivoted spindle and to the spring arm 8 which forms the bobbin-retaining member.

The bobbin-retaining member 9 has an inwardly turned fork or notched hook 9^b to permit it to form contact around the outer surface of the cop-tube which, in normal operative position, it grips tightly against the interior spindle blade 4. A stop pin 10 is inserted transversely of the shuttle body in the space between the bobbin-gripping member 9 and the forward end of the head portion 3 of the spindle so that, when the spindle is swung outwardly to open position, it will form a stop to engage the member 9 and arrest its pivotal movement, while allowing further outward movement of the spindle to continue, thereby separating the spindle-supported cop tube from the forward gripping portion 9^b of the cop-gripping member so as to entirely release the retaining engagement therewith and allow the cop tube to be easily withdrawn and another cop tube inserted in its place.

The bobbin-retaining arm 8 may be made of fairly heavy spring steel and at its rear end is riveted or otherwise firmly secured to the heel 3^a of the spindle in such relation as to normally exert an upward pressure against the underside of the bobbin-gripping member 9 to press the same into gripping engagement with the adjacent end of the cop-tube. The forward end of the bobbin-retaining member is turned inwardly to form an interiorly grooved fork or hook 8^a, adapted to pass into a usual peripheral groove in the base of an ordinary bobbin. The position of such a bobbin is indicated in outline by dotted lines in Figure 3.

It will be observed that the members 8 and 9 are so related, when the spindle is in operative position for weaving, that the spring arm 8 is slightly pressed away from

the straight line to exert an upward thrust against the pivotal gripping member somewhat forwardly of the axial center of the latter with the two members extending in substantial parallelism. This pressure in front of the pivotal axis not only pinches the gripping portion 9^b tightly against the cop tube, when the parts are in operative position, but also tends to cause the loosely mounted member 9 to swing about its axis 75 when the spindle blade is swung to open position, until the member 9 comes into contact with the stop pin 10, at which position further movement of the cop-gripping member is positively prevented. The further swinging movement of the spindle, carrying with it the attached spring arm 8, causes the spring arm to assume an angular relationship to the member 9 with the point of contact or thrust of said spring arm 85 against the member 9 advancing around the curved front end portion of the cop-gripping member.

By this arrangement and action the point of resistance to the continued revolution of the spring arm 8 is shifted well toward the forward end of said arm, with the consequence that said pressure or stop action is applied at an increased distance from the point of attachment, thereby permitting the greater part of the length of the spring arm 8 to participate in the flexing action caused by the further outward swing of the spindle. This long leverage eases the strain on the spring arm, and at the same time giving 100 greater resilience with the result that a heavier spring arm 8 may be used without increasing the resistance to opening the spindle. As the cop-gripping or retaining member need not be made of spring metal 105 at all, as it requires no flexing to properly perform its function, it will be seen that both the retaining members may be made of very strong and durable construction so as to avoid the breakage of these parts which 110 is a common occurrence in other constructions used for this purpose.

What I claim is:

1. In a weaving shuttle, the combination of a shuttle body, a cop and bobbin spindle pivotally mounted in the rear end of the shuttle to swing outwardly for the removal of cop or bobbin, a spring arm secured to the heel end of the spindle and having its forward end inwardly turned to engage and retain a bobbin, a pivoted cop-retaining member loosely mounted on the pivotal axis of the spindle and provided with an inwardly turned cop-engaging portion at its forward end to engage and retain a cop tube on the spindle blade, said cop retaining member being disposed to be pressed into engagement with a blade-carried cop when the parts are in proper position for weaving 130 and to itself form a stop abutting against

said spring arm when the spindle is swung out for removal of cop tube or bobbin, substantially as described.

2. In a weaving shuttle, the combination 5 of a shuttle body, a pivoted spindle mounted upon a transverse pivot pin in the rear end portion of the shuttle, a spring arm formed at its forward end to form retaining engagement with a bobbin carried by the 10 spindle, and secured at its rear end to the rear or heel end of the spindle, a cop-engaging and retaining member loosely mounted on the pivoted pin to permit rocking movement, a stop member arranged between the 15 spindle blade and the cop-engaging member to limit the pivotal movement of the latter, the spring arm being arranged to rock the forward end of the cop-engaging member into engagement with the cop when the 20 spindle is in normal weaving position and to be engaged and arrested by the forward end of the cop-engaging member when the spindle is swung out of the shuttle, substantially as described.

25 3. In a weaving shuttle, the combination with a shuttle body, of a blade pivotally mounted near its rear end on a transverse axis in the rear part of the shuttle, cop-gripping and bobbin-retaining members 30 mounted respectively on the said pivotal axis and on the heel end of the spindle so that, as the spindle is swung out of the shuttle, the relation of said members changes from a parallel to an angular relation, and a 35 stop arranged to limit movement of the cop-gripping member about its axis and by engagement of the forward end of said cop-gripping member with the spindle-supported member preventing the latter from swinging 40 further with the outwardly moving spindle, substantially as described.

45 4. In a weaving shuttle, the combination with a shuttle body, a spindle mounted to swing upon a transverse pivot pin located in the rear portion of the shuttle body, an

independently mounted pivoted cop-engaging member, a stop for limiting the outward swing of the cop-engaging member before the spindle has completed its outward swing, a spring arm secured to the heel end of the 50 spindle to normally press the cop-engaging member against a cop on the spindle, substantially as described.

5. In a weaving shuttle, the combination 55 with a shuttle body, a spindle pivotally mounted on a transverse pivot pin located in the rear portion of the shuttle, a spring arm secured at its rear end to the heel end of the spindle and terminating at its forward end in an inwardly turned bobbin-retaining member, an intermediate arm between the spring arm and the spindle pivotally mounted on said pivot pin to permit a limited swinging movement with the outwardly swinging spindle, until engaged by 60 a stop, said pivoted arm acting to resist the pressure of the spring arm toward the pivotal axis when the spindle is in normal weaving position and to limit the movement of the forward end of said spring arm with 65 the outwardly swinging spindle by pressure applied to said arm near its forward end, substantially as described.

6. In a weaving shuttle, the combination 75 of a shuttle spindle provided with a transverse pivot pin, a bobbin-retaining spring arm secured to the heel end of the spindle in substantial parallelism with the spindle axis, an intermediate arm pivotally mounted on the pivot pin to swing with the spindle until 80 engaged by a stop, said intermediate arm forming a resisting contact with the spring arm at all times, the point of such contact shifting toward the forward end of the spring arm as the spindle blade is swung 85 to open position, substantially as described.

In witness whereof, I have subscribed the above specification.

GEORGE A. LITCHFIELD.
